US0D1036426S

(12) **United States Design Patent** (10) **Patent No.:** **US D1,036,426 S**
(45) **Date of Patent:** **** Jul. 23, 2024**

(54) **STAND FOR AUDIO EQUIPMENT**

(71) Applicant: **Shenzhen Wuwai Creative Design Co., Ltd**, Shenzhen (CN)

(72) Inventor: **Yulin Li**, Shenzhen (CN)

(**) Term: **15 Years**

(21) Appl. No.: **29/912,514**

(22) Filed: **Sep. 20, 2023**

(51) **LOC (14) Cl.** **14-01**

(52) **U.S. Cl.**

USPC **D14/229**

(57) **CLAIM**

The ornamental design for a stand for audio equipment, as shown and described.

DESCRIPTION

FIG. 1 is a perspective view of a stand for audio equipment, showing my new design;

FIG. 2 is a another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the stand for audio equipment that form no part of the claimed design.

1 Claim, 8 Drawing Sheets
